UNITED STATES PATENT OFFICE

FLETCHER D. GRUND, OF WESTON, OHIO, ASSIGNOR TO THE AMERICAN SWISS COMPANY, OF TOLEDO, OHIO, A CORPORATION OF OHIO

DOOR-LATCH UNIT

Application filed August 23, 1929. Serial No. 388,004.

This invention relates to door latches of the type particularly adapted for use on vehicle bodies having inside and outside handles for retracting the latch bolt and also 5 provided with dogging means for rendering the outside handle inoperative by manipulation of the inside handle.

An object of this invention is to provide a simple and efficient door latch in which 10 the parts are compactly arranged and in which the dog for the outside-controlled roll-back projects through a cut-out portion of the latch bolt into position to be engaged by a part of the inside-operated bolt-retracting mechanism.

Other objects of the invention are to provide a simple and efficient door latch having the new and improved features of construction, arrangement, and operation hereinafter 20 described.

The invention is shown by way of illustration in the accompanying drawings, in which—

Figure 1 is a side elevation of the door 25 latch, a portion of the inside bolt-retracting mechanism being broken away; and Fig. 2 is an edge view of the parts shown in Fig. 1.

The illustrated embodiment of the invention comprises a door latch having a back 30 plate 1 provided with an outwardly extending flange 2 having an opening through which projects the head 3 of the latch bolt. Integral with the flange 2 is an extension 4 in parallel relationship with the back plate 1. The extension 4 provides a guide for the bolt head 3 and produces a more compact and sturdy construction than where in previous 35 constructions the flange is continued at substantially right angles to the back plate 1. Secured by rivets 5 to the bolt head 3 is the bolt 6 which is normally held in latching position by a coil spring 7 bearing against a lug 8 on the bolt.

The latch bolt is retractable from the out- 45 side of the door in a well known manner by a roll-back 8^a which is normally disposed in a notch 9 formed in the bolt 6. The roll-back unit is secured to the back plate by a cover plate 10 which engages an embossed 50 portion 11 on the back plate. Integral with

the roll-back 8 is a dogging extension 12 having a notch 13 to receive a dog 14.

The dog 14 is pivoted to a pin 14^a on the embossed part 11 of the back plate and is formed with a finger 15 which projects into the space between the latch bolt 6 and the back plate 1. It will be observed that a portion 16 of the latch bolt is engageable with the back plate 1 and the forward portion thereof is spaced from the back plate. 55

The latch bolt 6 is retracted from the inside of the door by a suitable control lever connected to a longitudinally disposed strap 17 which has an elongate slot 18 in one end portion to which the bolt is connected by a 60 pin 19. This provides a lost motion connection between the strap and bolt so that the door may be slammed, causing retraction of the latch bolt without disturbing the inside 65 retracting mechanism, as will be readily understood. 70

Formed in the latch bolt 6 is an elongate opening or cut-out 20, in this instance in the form of a longitudinally elongate slot, and the inner end of the strap 17 normally extends slightly into the region of this opening. Extending outwardly at substantially right angles from the finger 15 of the dog is an extension 21 which in the normal position of the parts bears against the end of the strap 17, a coil spring 22 on the dog serving to hold the finger 15 in this position. A stop 23 constituting an end portion of the spring 22 is provided against which the dog 14 abuts when the strap 17 is moved to the right of 75 Figure 1 to hold the extension 21 in position to be engaged by the strap 17 when the latter is moved away during bolt-retracting operation. 80

It will be observed that normally the roll-back may be operated to retract the bolt, the dog 14 being held out of dogging position. When it is desired to render the outside handle inoperative, the inside operating handle is moved in the reverse direction to the bolt-retracting operation in such manner that the strap 17 is moved to the left of Figure 1 to position the dog as shown by dotted lines, in which the finger 15 is swung to the left and the dog 14 engages in the notch 13 of the roll- 85 90 95 100

back extension 12. Any suitable means may be provided for holding the strap 17 in this position, a desirable arrangement being shown in the co-pending application of Fletcher D. Grund and H. W. Rightmire, Serial No. 388,003, filed August 23, 1929, entitled "Remote control for door latches."

In order to release the roll-back, it is merely necessary to return the strap 17 to normal position, the spring 22 serving to move the dog 14 out of engagement with the roll-back extension. This is done automatically when the door is opened from the inside, the movement being first to release the dog and subsequently to retract the latch bolt.

By the above described arrangement the dog and latch bolt are compactly arranged, affording not only an extremely simple construction, but an exceptionally sturdy and rugged arrangement. It will be understood that the above description is given by way of illustration and not of limitation and changes in construction, arrangement and operation may be effected without departing from the spirit of the invention.

What is claimed is:

1. A door latch comprising a back plate, a spring-tensioned latch bolt slidable over said back plate, a roll-back for retracting said latch bolt, a movable dog engageable with said roll-back for blocking movement thereof, a strap having a lost motion connection with said bolt for retracting the same, said bolt having an apertured portion, and an extension on said dog projecting through said apertured portion into the path of movement of said strap whereby movement of said strap in non-bolt-retracting direction actuates said dog to dogging position.

2. A door latch comprising a back plate, a spring-tensioned bolt slidable over said back plate, a roll-back for retracting said latch bolt, a pivoted dog disposed intermediate said bolt and back plate engageable with said roll-back for blocking movement thereof, a strap having a lost motion connection with said bolt for retracting the same, said bolt having a longitudinally elongate apertured portion, and an extension projecting at substantially right angles to the plane of said dog into said apertured portion and positioned in the path of movement of said straps, whereby movement of said strap in non-bolt-retracting direction actuates said dog to dogging position.

3. A door latch comprising a back plate, a spring-tensioned bolt slidable over said back plate, a roll-back for retracting said latch bolt, a pivoted dog interposed between said bolt and back plate engageable with said roll-back for blocking movement thereof, spring means normally holding said dog out of dogging position, inside retracting means for said bolt including a part having a lost motion connection with said bolt, said bolt having a longitudinally elongate apertured por-

tion, and an extension on said dog extending into said apertured portion and positioned in the path of movement of said part, whereby movement of said inside retracting means in non-bolt-retracting direction actuates said dog to dogging position.

In testimony whereof I have hereunto signed my name to this specification.

FLETCHER D. GRUND.
